INVENTOR

William H. Pugh

BY *George S. Webster*

ATTORNEY

UNITED STATES PATENT OFFICE.

WILLIAM H. PUGH, OF SACRAMENTO, CALIFORNIA.

GAME DEVICE.

Application filed April 30, 1924. Serial No. 709,989.

To all whom it may concern:

Be it known that I, WILLIAM H. PUGH, a citizen of the United States, residing at Sacramento, county of Sacramento, State of California, have invented certain new and useful Improvements in Game Devices; and I do declare the following to be a full, clear, and exact description of the same, reference being had to the accompanying drawings, 10 and to the characters of reference marked thereon, which form a part of this application.

This invention relates to improvements in accessories to be used in connection with the 15 playing of the game known as "Mah jongg", "Ma cheuck" and by other names.

My principal object is to provide a device to receive one of the tile used in playing the game as it is discarded by a player, so as to 20 temporarily render such tile more readily visible to the succeeding players than if it were at once placed on the table with the other discarded tile as is now customary.

Another object is to provide a device for 25 the purpose which has symbols impressed thereon at opposed points, the device being adapted to be turned as may be necessary so that the symbols face the different players whose positions, corresponding to these symbols, are arbitrarily fixed for each hand or 30 game by the rules of the game, but which it is sometimes hard to remember.

The advantages had with the use of my 35 device will therefore be appreciated by those who play the game.

A further object of the invention is to produce a simple and inexpensive device and yet one which will be exceedingly effective for the purposes for which it is designed.

These objects I accomplish by means of 40 such structure and relative arrangement of parts as will fully appear by a perusal of the following specification and claim.

In the drawings similar characters of reference indicate corresponding parts in the 45 several views:

Fig. 1 is a perspective view of my device, showing the same as disposed in connection with the wall of tile used in playing the 50 game.

Fig. 2 is a sectional elevation of the device.

Fig. 3 is a top plan view of the same.

Referring now more particularly to the characters of reference on the drawings, the 55 device consists of a pedestal or block 1, or any desired shape and size, but preferably of frusto-conical form as shown. The top of this block is preferably formed with a slight depression as at 2, whose area is sufficient to receive and support a single one of the tile 3 used in playing the game. The sides of the pedestal have painted or cut 60 therein at diametrically opposed points and in readily legible form letters 4 denoting the various winds, each player being arbitrarily assigned one such wind, as is well known.

Also arranged in connection with the wind letters are numbers 5 which arbitrarily have 70 a fixed relation to the letters.

In playing the game, the player who is "East Wind" is chosen in the customary manner, and the pedestal is then set on the playing table, centrally of the walls of tile, 75 with the letter E facing the corresponding player. The other letters on the pedestal will then automatically face the other players in the proper relation to their respective positions, and should any player temporarily 80 forget which "Wind" he is, he has only to glance at the pedestal in front of him to be reassured on this point.

When a player discards a tile while playing the game, instead of placing it on the 85 table along with other similar tile, he places it on the top of the pedestal, where it is in plain and unmistakable view of the other players. The succeeding player may then take up this tile and place his own discard 90 tile on the pedestal instead, or if he does not desire to use the original tile, he dislodges it from the pedestal by his own discard tile, since only one tile at a time can occupy 95 the top of the pedestal. By reason of the depression 2, the tile will not slide off the pedestal too easily, or by any jar imparted to the table.

From the foregoing description it will be 100 readily seen that I have produced such a device as substantially fulfills the objects of the invention as set forth herein.

While this specification sets forth in detail the present and preferred construction 105 of the device, still in practice such deviations from such detail may be resorted to as do

not form a departure from the spirit of the invention, as defined by the appended claim.

Having thus described my invention, what I claim as new and useful and desire to secure by Letters Patent is:

As a new article of manufacture, a device for use in connection with a game comprising

ing a pedestal having a flat top surrounded by a shallow rim, with arbitrary symbols permanently impressed on the sides of the pedestal at diametrically opposed points thereon.

In testimony whereof I affix my signature.

WILLIAM H. PUGH.
